(57) **CLAIM**

We claim the ornamental design for a specimen transporter, as shown and described.

DESCRIPTION

FIG. 1 is a front view of a specimen transporter of the present invention;

FIG. 2 is a rear view thereof;

FIG. 3 is a first side view thereof;

FIG. 4 is a second side view thereof;

FIG. 5 is a top view thereof;

FIG. 6 is a bottom view thereof; and,

FIG. 7 is a front and top perspective view thereof.

The broken lines in FIGS. 1, 5 and 7 are included for the purpose of illustrating portions of the specimen transporter that form no part of the claimed design.
